UNITED STATES PATENT OFFICE.

ATWOOD L. BOGGS, OF BOSTON, MASSACHUSETTS.

DESIGN FOR A COOLER.

41,748.

Specification for Design.

Patented Sept. 5, 1911.

Application filed February 11, 1911. Serial No. 608,137. Term of patent 14 years.

To all whom it may concern:

Be it known that I, Atwood L. Boggs, a citizen of the United States, residing at Boston, in the county of Suffolk and State of Massachusetts, have invented a new, original, and ornamental Design for Coolers, of which the following is a specification, reference being had therein to the accompanying drawing.

The new design for a cooler is shown in the accompanying drawing, which is a side elevation thereof.

I claim:

The ornamental design for a cooler, as shown.

In testimony whereof I hereunto affix my signature in the presence of two witnesses.

ATWOOD L. BOGGS.
